UNITED STATES PATENT OFFICE.

ROBERT A. HARRIS, OF TUCSON, ARIZONA TERRITORY.

BUILDING-BLOCK AND MANNER OF ASSEMBLING.

No. 882,833.

Specification of Letters Patent. Patented March 24, 1908.

Application filed September 20, 1903. Serial No. 335,333.

To all whom it may concern:

Be it known that I, ROBERT A. HARRIS, a resident of Tucson, in the county of Pima and Territory of Arizona, have invented certain new and useful Improvements in Building-Blocks and Manner of Assembling; and I do hereby declare the following to be a full, clear, and exact description of the invention, such as will enable others skilled in the art to 10 which it appertains to make and use the same.

My invention relates to improvements in building blocks and manner of assembling, the object of the invention being to provide an improved building block having longitudinal and lateral intersecting grooves or recesses in at least one face, to receive tie rods to secure the blocks together and the parallel walls or parts of the same wall, and the invention consists in certain novel features of construction and combinations and arrangements of parts as will be more fully hereinafter described and pointed out in the claims.

In the accompanying drawings, Figure 1 is a perspective view of a building block embodying my improvements. Fig. 2 is a plan view illustrating one form of wall construction, and Figs. 3, 4, 5, 6, 7, and 8, are views of modifications.

1 represents my improved building block which is provided on one or more faces or edges with a longitudinal central groove or recess 2, and a series of intersecting transverse grooves or recesses 3. The block is preferably proportioned so that the width or height will be an even division of the length and the thickness an even division of the width or height.

The blocks, which are preferably composed of cement, concrete or other composition, are laid in the wall with the grooved face uppermost, and are disposed with their meeting ends arranged alternately, that is to say the meeting ends of one row of blocks located above the center of the blocks in the rows above and below.

In building a double wall, the inner and outer walls are parallel and spaced apart, and divisional columns 4 are located at the corners or at other points between the walls and these columns may be made up of a number of said blocks 1 or modifications thereof securely tied together in any desired manner. Tie rods 5, are located in the longitudinal grooves 2, run longitudinally of the wall and may be secured at their ends by nuts 6, or

these tie rods may turn at the corner of the wall, as illustrated in connection with the inner wall, or may be secured merely by the action of the covering cement placed thereon 60 in the grooves or recesses. Lateral tie rods 7, are located in the grooves 3 of both walls, secured by nuts, or otherwise, and securely tie the parallel walls together. As many of the lateral tie rods 7 may be employed as is 65 found necessary and they may be secured to the longitudinal rods as shown at 9, or may secure ornamental blocks 10 of any ornamentation or other parts such as joist, beams girders or other necessary parts of building to 70 the walls, and the longitudinal rods 5 may also secure ornamental blocks 11 or other ornamental or important features to the wall, viz: frames for window or doors and in fact, the tie rods may be disposed in a great variety 75 of ways to best secure the wall together and withstand the uses to which the wall is to be put. By constructing a wall of this type, any dampness which may find its way through the outer wall will not be transferred 80 to the inner wall as there is no connection between the walls other than the tie rods, and this is a great improvement over the hollow walls such as heretofore made where the inner and outer walls are connected by integral 85 or connected webs on the walls.

In all the uses of the tie rods, a filling of cement is placed in the grooves to surround or hide the tie rods and further secure the walls into a single mass.

Having fully described my invention, what I claim as new and desire to secure by Letters-Patent is:

1. The combination of parallel walls, each composed of building blocks having alining longitudinal grooves, said blocks having transverse grooves extending from side to side thereof and intersecting the longitudinal grooves, longitudinal tie rods extending continuously through the longitudinal grooves 95 and securing the blocks of each wall together, and transverse tie rods passing through the transverse grooves and tying the two walls together and securing means at the ends of said longitudinal and transverse 100 rods.

2. The combination of two parallel walls spaced apart and each composed of building blocks, each block having a longitudinal groove extending from end to end thereof 110 and each block having a transverse groove extending from side to side thereof, tie

rods passing through said longitudinal and transverse grooves, means independent of the grooves for securing said blocks and walls, and columns between the parallel walls.

3. The combination with parallel walls composed of building blocks each block having intersecting longitudinal and transverse grooves in its upper face, each longitudinal groove extending from end to end of a block and each transverse groove extending from side to side of a block, longitudinal tie rods in said grooves securing the blocks of a wall

together and transverse tie rods securing the two walls together, columns between the walls, and ornamental blocks secured to and adapted to bear against the wall formed by said blocks.

In testimony whereof, I have signed this specification in the presence of two subscribing witnesses.

ROBERT A. HARRIS.
